UNITED STATES PATENT OFFICE.

WILLIAM MORTON TIPTON, OF CYRENE, MISSOURI.

FENCE.

SPECIFICATION forming part of Letters Patent No. 390,268, dated October 2, 1888.

Application filed May 13, 1887. Serial No. 238,129. (No model.)

To all whom it may concern:

Be it known that I, WILLIAM MORTON TIPTON, a citizen of the United States, residing at Cyrene, in the county of Pike and State of Missouri, have invented certain new and useful Improvements in Fences; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The invention relates to improvements in fences; and it consists in the construction and novel combination of parts hereinafter described, illustrated in the drawings, and pointed out in the appended claim.

In the accompanying drawings, Figure 1 represents a view of one side of a portion of a fence embodying the invention. Fig. 2 represents a view of a portion of the opposite side of the same.

Referring to the drawings by letters, A designates one of the fence-posts of a single thin piece having two opposite flat sides, and provided at a suitable point near its bottom with the similar opposite offsets, a a' , standing outward from its edges on each side, the lower edges of which offsets are at right angles to the axis of the post. The edges of the point a of the post below the offsets converge at equal angles and come to a point in the axis of the posts. The opposite edges of the post are provided with the pairs of non-aligned notches a^2 , for a purpose hereinafter explained. The post may be either of wood or iron, and should the latter be used it should be galvanized.

B B are the rails, made, preferably, of galvanized plate-iron and provided at points adjoining the posts with the non-aligned openings b b' , which register with the notches a^2 of the adjacent post-edges.

C are wires, the ends of which are passed through the pairs of non-aligned notches a^2 , and through the corresponding slots, b b' , and are bent down on the outer surfaces of the rails, thus binding the rails firmly to the posts.

The fence as described is simple of construction, can be easily and quickly put up and taken down, and is not likely to be broken or get out of repair, as it consists of three sets of parts

only—the slotted rails, the binding-wires, and the posts—the parts of which—namely, the uprights, the offsets, and points—are integral. 55 The notches a^2 on the opposite edges are not aligned, in order not to reduce the width of the metal too much at any one point.

When the fence is up, the offsets support the posts in the line of direction of fencing, 60 the same being supported laterally by the whole width of the point. It is not intended that the offsets shall enter the ground, but that they shall rest thereon, and, having their lower edges at right angles to the axis of the 65 posts, they will support the latter in a vertical position. It will thus be seen that the fence is composed of three parts, which are the posts pointed at their lower ends, so that they can be quickly driven into the ground, and 70 provided with the integral offsets a' in the line of the fencing, and the series of notches a^2 , which do not register on opposite sides, the rails provided with non-registering slots near their ends, and the bent wires connecting the 75 rails to the posts.

I am aware that rails have been secured to the flat surfaces of posts by wires, and that offsets in the line of direction of fencing have been secured to posts, and such I do not claim, 80 broadly.

Having described my invention, I claim—

The herein-described fence, composed of three parts, which are the flat wide posts having the offsets a' , which stand in the line of 85 fencing, the pointed lower ends, a , by means of which they can be easily driven into the ground up to said offsets, and the non-registering series of notches a^2 in their edges above the offsets, the flat rails B, having the non-aligned slots b b' near their ends, which slots register with the corresponding notches of adjoining posts, and the binding-wires C, having their ends passed through the pairs of non-aligned notches and registering slots, and bent 90 downward toward each other on the outer surfaces of the rails, substantially as specified.

In testimony whereof I affix my signature in presence of two witnesses.

WILLIAM MORTON TIPTON.
